UNITED STATES PATENT OFFICE.

CHARLES W. QUIN, OF CENTRALIA, WASHINGTON.

COMBINED TIE-PLATE AND SPIKE-RETAINER.

1,072,991.

Specification of Letters Patent.

Patented Sept. 9, 1913.

Application filed February 19, 1913. Serial No. 749,498.

To all whom it may concern:

Be it known that I, CHARLES W. QUIN, a citizen of the United States, residing at Centralia, in the county of Lewis and State 5 of Washington, have invented new and useful Improvements in Combined Tie-Plates and Spike-Retainers, of which the following is a specification.

The present invention relates to combined 10 tie plates and spike retainers for railway construction, and resides in the construction, combination and operative arrangement of parts set forth in the following description and falling within the scope of the 15 appended claims.

In the drawings: Figure 1 is a top plan view illustrating my invention in applied 20 position upon a railway rail and the ties for the rail, Fig. 2 is a side elevation of the same, Fig. 3 is a longitudinal sectional view upon the line 3—3 of Fig. 1, Fig. 4 is a transverse sectional view on the line 4—4 of 25 Fig. 1, Fig. 5 is a top plan view of the plate, Fig. 6 is a perspective view of the spike 30 sustaining plate, Fig. 7 is a side elevation, partly in section, illustrating a modified form of the device, and Fig. 8 is a similar view of a still further modified form of the device.

While in the accompanying drawings, I have illustrated a satisfactory reduction of 35 my improvement to practice, it is to be understood that in carrying out the objects of my invention, the same is susceptible to embodiment in various forms of construction which will fall within the scope of the appended claims.

Referring to the drawings in detail, the 40 numeral 1 designates an ordinary railway tie, and 2 an ordinary railway rail. Arranged upon the tie 1, and providing a bearing for the base flange of the rail 2, is a tie plate 3. The plate 3 comprises a flat substantially rectangular metallic member and 45 is provided adjacent its corners with openings 4 for the reception of spikes 5, whereby the plate and rail are secured upon the tie 1. The heads of the spikes are adapted to engage with the base flanges of the rails adjacent the longitudinal edges thereof, and the plate 3 is provided at its opposite ends and central of the openings 4 with additional openings 5. The openings 5 communicate with countersunk depressions, and 50 arranged within said depressions are the heads 6 of threaded members, the shanks 7

of which pass through the openings 5 and project a suitable distance above the plate 3. The numerals 8 designate nuts which engage with the threaded shank 7 and which bear against the upper face of the plate 3. Resting upon the nut 8, and being provided with a suitable opening through which the shanks 7 project, is a spike retaining member 9. The member 9 is preferably of a rectangular formation, and has its sides, adjacent one of its ends provided with down-turned longitudinally extending flanges 10 and 11, so spaced as to frictionally engage with the opposite sides or faces of each of the nuts 8. Each of the members 9 overlie the head of the securing spike 5, as clearly shown in the drawings. Each of the members 9 is provided upon its upper face and adjacent its outer end with a spring catch 11, the same adapted to engage with a binding nut 12, which is screwed upon each of the stems 7 and which engages with the upper face of each of the members 9. By such a construction, it will be noted 50 that the members 9, which at all times overlie the heads of the spikes 5 upon the opposite sides of the rail provide a simple but effective means for preventing the loosening and the accidental withdrawal of the 55 spikes, incident to the vibration of the rails by the rolling stock passing thereover, which is entirely overcome, and danger of the spreading of the ties is materially reduced, if not entirely overcome. Furthermore, the 60 plates 3 effectively prevent the sinking of the rails to within the ties, and thus materially add to the life of the ties as well as the life of the rails.

In Fig. 7 I have illustrated a structure 65 somewhat similar to that previously set forth. Instead, however, of employing the headed threaded element 6 which passes through a non-threaded opening in the end of the tie plate 3, I provide the said plate 100 with a threaded opening 13, and arranged upon the plate, and above the said opening 13 is a washer 14, the outer perimeter of which is square or angular, and which has its opposite faces engaged by the flanges 105 10 and 11 of the spike-retaining plate 9. The plate is of a similar construction to that previously described, and is provided with an opening which registers with an opening in the washer 14 and the threaded 110 opening 13, and passing through these openings is the threaded stem 15 of a head mem-

ber 16, the head of the said member being engaged by the spring catch 11 of the plate 9.

In Fig. 8 the device is substantially similar to that described in connection with Fig. 7, except that instead of employing the washer 14, the plate 3 is provided at each of its ends with an integrally formed upstanding rectangular lug 17, which has its opposite faces engaged by the flanges of the spike retaining member 9.

From the above description, taken in connection with the accompanying drawings, the simplicity and advantages of the device, will, it is thought, be perfectly apparent to those skilled in the art without departing from the spirit or sacrificing any of the advantages of the invention.

Having thus described the invention, what I claim is:

- 20 1. A tie plate for railway rails comprising a flat rectangular member having spike openings at its corners adapted for the reception of spikes whose heads overlie the base flanges of the rail which rests upon the plate, a plate arranged upon the ends centrally of the spikes and adapted to overlie
- 25

and engage one of the spikes securing means for the plate, and a spring catch carried by the plate and co-acting with one of the elements of the securing means to retain the 30 said element against movement.

2. A tie plate for railway rails having spike openings for the reception of spikes whose heads engage with the base flanges of the rails, a headed threaded member arranged upon the plate at its ends and intermediate its spike openings, a member having an angular perimeter arranged upon the plate and engaged by the threaded member, a plate having flanges arranged upon the threaded member and disposed over the head of the spike and contacting therewith, a binding element for the plate, and a catch member carried by the plate and engaging the binding element.

In testimony whereof I affix my signature in presence of two witnesses.

CHARLES W. QUIN.
